UNITED STATES PATENT OFFICE.

KARL GUSTAV OELSNER, OF RIVERTON, WYOMING.

LIFE-SAVING DEVICE.

1,199,107.

Specification of Letters Patent. Patented Sept. 26, 1916.

Application filed July 28, 1915. Serial No. 42,451.

To all whom it may concern:

Be it known that I, KARL GUSTAV OELSNER, a naturalized citizen of the United States, and a resident of Riverton, in the county 5 of Fremont and State of Wyoming, have invented new and useful Improvements in Life-Saving Devices, of which the following is a full, clear, and exact description.

This invention relates to improvements in 10 life saving devices, boats and rafts, and the objects of my improvement are first, to construct the necessary material in such a form as to build an efficient raft therewith in a short time, second, to allow for the building 15 of a sufficient number of such rafts to accommodate most of the passengers if all other devices have failed and, third, to provide said passengers with food and drinking water.

20 To such end, the invention consists essentially in a log float raft having log floats each composed of three equal pieces pinned together by means of a plurality of long pins passing through registering holes in 25 said pieces, each of said pins provided with a short cross pin passing through a hole in each lower end.

The invention also consists in a log float raft having a plurality of transverse boards 30 provided with holes to register with the holes in the log floats.

The invention further consists in a log float raft carrying in the middle a double walled provision box.

35 The invention is illustrated in the accompanying drawings in which—

Figure 1 shows a top or plan view of the raft with the provision box in conventional form, Fig. 2 shows a longitudinal side view 40 of the raft with the provision box omitted, Fig. 3 shows a single log in its three parts, and Fig. 4 shows the provision box in detail and in conventional form.

In order to enable those skilled in the art 45 to make and use my invention, I will now describe the same in detail.

Numeral 10 indicates the log floats, three or five, as the case may be. Each log is composed of three pieces of equal dimensions 50 10^a, 10^b and 10^c. The length of the logs depends on the length of the cross boards 11, and is always double the length of said cross boards; for example, if the boards are 10 feet long the logs will be made 55 20 feet long. Each board is 2 or 3 inches thick, proportionately broad, and has 5

holes spaced equidistant. Each log has ten holes to register with the respective holes of the ten cross boards. The middle piece 10^b of each log is provided at each end with a protruding pin, said pin provided with a hole. Near the ends of each built up log is fixed a leather or brass ring 13, to bind the three separate pieces together. Through the ten holes of each log, vertical pins 12 60 are driven which are enveloped with paper to prevent slipping. These pins extend above and below said logs and have on each end a small hole. Through the hole in the lower end of each pin is driven a small cross 65 tie pin or nail 12^a, so as to engage the lower side of said log and prevent upward slipping of the vertical pin 12.

Numeral 14, Figs. 1 and 4, shows the provision box having a length equal to 70 twice its width and of medium height. Said box is made double walled and is adapted to contain food and drinking water and other necessities. A small door is provided on one side of the box and a ring 15 on each 75 of the four sides.

The logs are painted red, the boards white and the box blue. When not in use, the logs and boards are tied up bundle-wise, thereby occupying less space than an ordinary built up raft. In such a way, material for a large number of rafts may be in readiness on deck. In case of ship wreck 80 this material, logs, boards, and boxes, which are located on the deck or are hoisted onto the deck, slip automatically into the water. There they are expanded and assembled as follows: The boards are laid over the tops of the vertical pins of the logs and ropes 85 are laced through the holes of said pins and around the logs and boards in such a manner as to cross both above and below the raft in passing from one pin to another. The additional two holes in each cross board may be utilized to lash two more logs 90 in place if the material is at hand and time is available. Lastly, the provision box is lashed in place by means of ropes passed through the rings 15 and engaging the boards and logs nearby. The drawing also 95 shows two end cross pieces 11^a provided with holes to engage with the protruding pins at the end of each log. The ropes are also passed through the holes in said protruding pins.

100 I claim:

105 A life raft comprising a plurality of

longitudinally extending log floats and transverse boards extending across said floats, said boards and floats provided with registering holes, securing means comprising vertical tie pins in said holes and cross tie pins extending through holes in the lower ends of said tie pins below the bot-

tom of said floats and flexible lacing extending above and under said floats and boards.

KARL GUSTAV OELSNER.
